UNITED STATES PATENT OFFICE.

GIOVANNI EMANUELE ELIA, OF PARIS, FRANCE, ASSIGNOR TO VICKERS LIMITED, OF WESTMINSTER, ENGLAND.

AUTOMATIC ANCHORING DEVICE FOR SUBMARINE MINES.

1,072,928.

Specification of Letters Patent. Patented Sept. 9, 1913.

Application filed February 27, 1913. Serial No. 751,025.

To all whom it may concern:

Be it known that I, GIOVANNI EMANUELE ELIA, a citizen of Italy, and residing at Hotel de Crillon, Place de la Concorde, Paris, France, have invented certain new and useful Improvements in and Relating to Automatic Anchoring Devices for Submarine Mines, of which the following is a complete specification.

10 This invention has for its object improvements in automatic anchoring devices for submarine mines which render it possible to insure the normal and secure succession of the several operations of mine laying and 15 also the smooth and easy unwinding of the mooring cable.

In submarine mines provided with a lead, in which the connecting cable is attached to the anchor proper, as the mine and its anchor are intended to be launched in the water in a single operation, it frequently happens that owing to the difference of the weights of the constituent parts, especially when the launching is effected at a considerable height above the surface of the water, the normal order of these parts is inverted and the anchor or even the mine proper may come into contact with the water before the lead, thereby impairing the precision of the 30 launching owing to the fact that the cable of the lead becomes wound around the anchor thereby reducing its length, so that the mine may even be wrecked. This defect is still further increased by the fact that during the unwinding of the mooring cable, this cable being inefficiently guided may bind and wreck the mine or at all events cause it to be moored at an incorrect depth. In accordance with the present invention, which 35 obviates these defects, mechanism is provided which releases the lead before the assemblage is placed in the water, and the lead is provided with an automatic device for regulating the depth of mooring, and at 40 the same time insuring the free unwinding of the mooring cable.

An embodiment of the invention is illustrated by way of example in the accompanying drawing, in which:—

50 Figure 1 is a section of the anchor before it is placed in the water. Fig. 2 is a partial view showing the parts occupying a different position. Fig. 3 is a detail view of the lead in section.

55 Before the mine is placed in the water,

the lead *a* is supported by a ring *b* in a hook *c* pivoted to the body of the anchor and held in its closed position shown in Fig. 1 by a ring *d* arranged at the end of a rocking lever *e* pivoted at *f* to the wall of the anchor and 60 pivoted to a rod *g* which is itself connected by its lower extremity with an arm *h* integral with a tappet *i* provided at *j* and projecting below the anchor inside running rails *k*. At the outer end of this rail a stop *m* is 65 provided upon the path of the tappet *j*.

The lead (Fig. 3) comprises a winch *n* carrying a certain length of cable *y* and mounted upon a shaft *o* which presents a threaded portion *p* to which a nut *q* is fitted. 70 This nut which externally presents an appropriate polygonal form, is housed in a passage of the same form *r* in such a manner as to prevent it from participating in the rotation of the winch and the passage is 75 obturated by a part *s* forming a bearing for the shaft of the winch and held in position by a screw *t*.

The anchor proper comprises, in its upper face *u* a notch *v* forming a slideway in which a slide block *x* is housed in such a manner as to be capable of displacement; this block is perforated for the passage of the mooring cable of the mine.

The operation is as follows:—On mounting the lead, in the first place the cable *y* is wound upon the winch *n*, whereupon the nut *q* is arranged in the proper position by hand so that the cable cannot unwind at the moment of launching the mine, beyond the 80 amount corresponding to the depth of mooring of the mine this adjustment being effected by means of a graduated scale for example, whereupon this lead is hooked to the hook *c* by means of its ring *b*. At the moment of launching the mine, the tappet *j* strikes the fixed stop *m* arranged at the end of the rail *k* and is pressed back; by the intermediary of the rod *g* this tappet causes the ring *d* to assume the position illustrated 90 in Fig. 2, which causes the jointed hook *c* to open thereby allowing the lead to fall before the anchor itself has reached its mooring point. The cable *y* of the lead unwinds in rotating the winch *n* and its shaft *o* *p* until the nut *q* becomes blocked against the winch thus preventing any rotation of the latter, and consequently limiting the unwinding of the cable to the 100 predetermined length. While the anchor is de- 110

scending in the water, its winch α rotates in the usual manner to allow the proper length of mooring cable to unwind, and the uniform unwinding of the cable is insured by the arrangement of the slide block α which constantly follows the cable to its point of departure from the winch in traveling along the slideway v . The novel device thereby provides for the exact and precise 10 mooring of the mines at the desired place and depth without risk of wrecking the mine, because on the one hand the lead always precedes the anchor in its descent and because the depth of mooring is regulated 15 at the start by the freedom to unwind which is afforded to the cable of the lead by means of the nut q and furthermore, the mooring cable for the mine is constantly guided in its unwinding and can neither 20 bind nor become damaged. The connection between the lead and the anchor might obviously present any desired form or arrangement other than that described, provided that this lead is thereby necessarily thrown 25 into the water before the anchor. For example, the office of lead might be fulfilled by the front group of the wheels supporting the anchor and its mine upon the running rails, the anchor being merely supported upon the 30 corresponding axle. In order to facilitate adjustment, the lead itself might present a nut q in two parts, one circular for example and screwed upon the shaft p of the winch and rotating freely in the passage r , and the 35 other fitted in the passage r and adapted to be rendered integral with the first in any appropriate manner, these parts being readily accessible as soon as the outer bearing s has been removed. Finally, the slide block α 40 might comprise any convenient device such as a pulley or other member for facilitating the passage of the mooring cable.

The invention is applicable to submarine mines of all kinds.

What I claim is:

1. In an anchoring device for submarine mines, an anchor, a lead line carrier, means for supporting the carrier from the anchor, and means for automatically releasing the carrier immediately preceding the launching 50 of the anchor.

2. In an anchoring device for submarine mines, an anchor, a lead line carrier, a movable member on the anchor for supporting the carrier, means for locking the movable member in position, and means for automatically operating the locking means to release the said movable member immediately preceding the launching of the anchor. 55

3. In an anchoring device for submarine mines, an anchor, a lead line carrier, a pivoted member on the anchor and with which the carrier engages, a pivoted lever on the anchor and engaging the pivoted member to hold it in position to support the carrier, a pivoted tappet on the anchor and connected with the lever, and a stop in the path 60 of the anchor for operating said tappet. 65

4. In an anchoring device for submarine mines, an anchor, a rail upon which the anchor travels, a lead line carrier formed with a ring, a pivoted hook on the anchor and with which the ring of the carrier engages, a pivoted lever on the anchor and having at its outer end a ring engaging the 70 hook, a pivoted tappet having an angular arm, a rod connecting the arm of the tappet with the inner end of the said lever, and a stop at the outer end of the rail and in the 75 path of the tappet. 80

In testimony whereof I have hereunto placed my hand at Rome, Italy, this eleventh day of February, 1913.

GIOVANNI EMANUELE ELIA.

In the presence of two witnesses—

GIOVANNI VOLATELLI,
TORELLA FONTANI.
